US00D987704S

(12) **United States Design Patent** (10) **Patent No.:** **US D987,704 S**
Jiang (45) **Date of Patent:** **** May 30, 2023**

(54) **GIMBAL CAMERA**

(71) Applicant: **Autel Robotics Co., Ltd.**, Shenzhen (CN)

(72) Inventor: **Juntian Jiang**, Shenzhen (CN)

(73) Assignee: **AUTEL ROBOTICS CO., LTD.**, Guangdong (CN)

(**) Term: **15 Years**

(21) Appl. No.: **29/735,635**

(22) Filed: **May 22, 2020**

(30) **Foreign Application Priority Data**

Nov. 22, 2019 (CN) 201930645930.6

(51) **LOC (14) Cl.** **16-01**

(52) **U.S. Cl.**

USPC **D16/218**; D16/202

(57) **CLAIM**

I claim the ornamental design for a gimbal camera, as shown and described.

DESCRIPTION

FIG. 1 is a front elevational view of a gimbal camera showing our new design;

FIG. 2 is a back elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

1 Claim, 7 Drawing Sheets
